ICE TRAY

James W. Jacobs, Dayton, Ohio, assignor to General Motors Corporation, Dayton, Ohio, a corporation of Delaware

Application September 17, 1938, Serial No. 230,466

9 Claims. (Cl. 62—108.5)

This invention relates to freezing devices for liquids and particularly to ice trays and grids therefor employed in household refrigerating apparatuses.

5 A general object of my invention is to provide an improved grid construction adapted to be removably disposed in an ice tray for dividing the interior of the tray into a plurality of ice block compartments and a novel method of removing 10 ice blocks from the tray and grid without applying heat thereto.

Another object of my invention is to provide a unitary metallic grid structure for an ice tray which is removable from the tray as a unit together with ice blocks adhering thereto and which structure has three substantially inflexible members or walls located one above the other in substantially the same vertical plane and forming a longitudinal partition carrying a plurality 20 of substantially inflexible transverse partitions and wherein the two upper members of the longitudinal partition are movable upwardly of the lower member thereof to move the top member lengthwise of the intermediate member to cause 25 a tilting or rotating movement of the transverse partitions for breaking the bond between ice blocks and the grid walls to thereby facilitate the harvesting of ice blocks.

It is a further object of my invention to provide, in a grid structure of the type described in the foregoing object, transverse partitions which are normally disposed in an upright acute angled position and are movable out of their acute angled disposition by movement of certain of the members or walls of the longitudinal partition relative to one another into another position to enlarge the ice block compartments formed therebetween for releasing ice blocks from the compartments.

40 A still further object of my invention is to provide a grid structure of the type described with a lever having a single direction of motion for elevating the unitary grid together with ice blocks adhering thereto from the tray and for elevating the intermediate and top members or walls of the longitudinal partition relative to the lower member or wall thereof to move the top member lengthwise of the intermediate member for causing tilting or rotation of the transverse partitions.

50 Still further and more specific objects and advantages of my invention reside in the construction and ease of operation of my improved grid structure and in novel combinations and arrangements of parts thereof as will more fully appear 55 in the course of the following description.

In the drawings:

Fig. 1 is a top plan view of a freezing device comprising a tray and a grid constructed in accordance with my invention removably disposed in the tray;

Fig. 2 is a side view of the freezing device disclosed in Fig. 1 and taken on the line 2—2 thereof showing the tray in section;

Fig. 3 is a view similar to Fig. 2 showing ice blocks in the freezing device and disclosing the grid structure and ice blocks therein elevated relative to the tray;

Fig. 4 is a view disclosing the grid removed from the tray and showing walls of the grid moved relative to one another for releasing ice blocks therefrom;

Fig. 5 is a vertical transverse sectional view of the freezing device taken on the line 5—5 of Fig. 2;

Fig. 6 is a vertical transverse sectional view 20 of the device taken on the line 6—6 of Fig. 2 showing the transverse grid walls interlocking two of the members of the longitudinal partition together; and

Fig. 7 is a vertical transverse sectional view 25 of the freezing device taken on the line 7—7 of Fig. 2 showing the connection of two of the members of the longitudinal grid partition with a third member thereof.

As before stated, my invention relates to a 30 freezing device of the type generally employed in household refrigerating apparatuses for producing small cubes or blocks of ice and reference to the accompanying drawings will be made to illustrate the invention. The freezing device includes 35 a metal ice tray 15 (see Fig. 1) having a unitary metal walled grid 16 removably disposed therein for dividing the interior thereof into longitudinal rows of ice block compartments 17. The tray 15 has side walls 18 (see Figs. 5, 6 and 7), a bottom 40 wall 19 and opposed end walls 21 and 22. The tray side walls 18 and the end walls 21 and 22 thereof diverge outwardly toward the top of the tray to facilitate removal of the grid and ice blocks adhering thereto from the tray. The walls 45 18, 21, and 22 of tray 15 have their upper edge rolled or bent over to form a rim 23 which extends continuously around the top of the tray to increase its structural strength. A portion of the metal tray 15 is extended downwardly from 50 rim 23, as at 24, at the front end 22 thereof and provides a mounting for a heavy metal piece 26 which has a handle 27 pivotally secured thereto as at 28. The legs of handle 27 are provided with a cam surface 29 adapted to engage the 55

tray support to break an ice bond between the tray and its support as will hereinafter be more fully described.

The unitary grid structure, generally represented by the reference character 16, is removably disposed within tray 15 and includes a plurality of inflexible metal walls which divide the interior of the tray into the longitudinal rows of cells or compartments 17. The grid structure 16 comprises a longitudinal partition 30 formed of or comprising three rigid metal members 31, 32 and 33. It will be noted that the major part of members 31, 32 and 33 are disposed one on top of the other and lie in substantially the same vertical plane with one another. The lower longitudinal member 33 of partition 30 has an upstanding end portion 34 offset, as at 35 (see Fig. 1), so as to position the end portion 34 adjacent and out of the vertical plane of an enlarged end portion 36 (see Fig. 4) of member 32. The opposite end of member 33 terminates in an upstanding portion 37 also offset, as at 38 (see Fig. 1), so as to position this end portion 37 of member 33 adjacent and out of the vertical plane of the ends 39 and 41 of members 32 and 31 respectively. The ends 39 and 41 of longitudinal members 32 and 31 are secured to longitudinal member 33 by rivets or the like 42 and 43 respectively which pass through the upstanding end portion 37 of member 33. A lever 45 having a handle end 46 and a short end 47 is provided with legs 48 and 49 (see Fig. 1). A stud or the like 51 staked or otherwise suitably secured to the one leg 49 of lever 45 extends into a suitable opening therefor provided in the upstanding end portion 34 of member 33. The opening within the end portion 34 of member 33 and the stud 51 provides a pivotal mounting support for lever 45 upon member 33. A stud or the like 52 also staked or otherwise suitably secured to the other leg 48 of lever 45 extends into an angularly disposed slot 53 provided in the enlarged end portion 36 of member 32. Slot 53 has an enlarged upper end portion 54, the purpose of which will be hereinafter described. The legs 48 and 49 of lever 45 straddle the members 32 and 33, and the studs 51 and 52 secured to the lever movably lock the ends 34 and 36 of members 33 and 32 respectively together. Thus, lever 45 is pivotally secured to or mounted on member 33 of the longitudinal partition 30 by a stud 51.

The upper member 31 of partition 30 has its end opposite the end 41 thereof terminating in spaced relation to a wall portion 55 of the enlarged end 36 of member 32 for a purpose to be hereinafter more fully described. This upper longitudinal member 31 of partition 30 has a plurality of equally spaced apart slots 57 cut inwardly of its top edge. Slots 57 are wider at their lower portion than at their top for a purpose which will become apparent in the description of operation of the grid structure. The intermediate member 32 of the longitudinal partition 30 has a plurality of equally spaced apart slots 58 cut inwardly of its bottom edge. These slots 58 cut or provided in member 32 are wider at their tops than at their lower portion for a purpose to hereinafter become apparent. The slots 57 in member 31 are, in the normal ice freezing position of the grid structure 16, disposed slightly to the right of slots 58 provided in member 32. Slots 57 and 58 are paired and each pair thereof is adapted to receive and hold in place upon the grid structure 16 a cross wall or partition which cooperates with the longitudinal partition to 75 divide the interior of tray 15 into the plurality

of ice block compartments 17. It, therefore, located a plurality of transverse partitions or rigid metal walls 61 upon the two members 31 and 32 of the longitudinal partition 30 and within the slots 57 and 58 prior to securing the members 31 and 32 to the lower member 33 of the longitudinal partition. Each first members 61 is provided with a vertically disposed opening therein for the reception of the members 31 and 32. One side of the opening in each member 61 is bounded by a straight vertical side wall 62 (see Fig. 6). The other side of the opening in each member 61 is formed or bounded by a short vertical wall portion 63 connected with a second vertical wall portion 64 by an angularly disposed wall portion 15 65 which is connected, by a short horizontal wall portion 66, with a third vertical wall portion 67. In assembling the transverse partitions 61 upon the grid structure 16, the member 31 is first passed through the opening in each partition 61 20 and is moved over so that the web portions thereof below the slots 57 lie against the wall portions 64 and 66. This temporary position of member 31 within the cross walls 61 leaves sufficient space within the opening provided in the wall 61 for the reception of the longitudinal member 32. The member 32 is then passed through the opening in each partition 61 to position the top wall of slots 58 provided therein against the bottom wall of the openings in partitions 61. The short angular wall portion 65 of the opening in each partition 61 permits the member 31 to then be moved upwardly of member 32 into vertical alignment therewith whereby member 31 rests upon member 32 while at the same time locking the transverse members 61 in place by the engagement of member 31 with wall portion 63 and member 32 with wall portion 67 of members 61. The assembled together members 31, 32 and 61 are then secured to member 33 by the rivets 42 and 43 and by the studs 51 and 52 of lever 45 to provide a unitary grid structure. It will be noted that the cross walls or partitions 61 each have a vertical slot 71 provided therein and extending upwardly from their bottom edge. This slot 71 permits the members 31 and 32 of the assembled sub-assembly comprising the members 31, 32 and 61 to be disposed in the same vertical plane with the lower member 33 since the slots 71 receive the member 33 during assembly of the structure. 50

The normal out of vertical alignment of slots 57 in member 31 relative to slots 58 in member 32 of the longitudinal partition 30 locates or normally maintains the cross walls or partitions 61 in an inclined or acute angled upright position 55 relative to the bottom of tray 15 or relative to the vertical disposition of longitudinal partition 30. This acute angled disposition of partitions 61 provides the ice block compartment 17 with a parallelogram shape in one direction of cross section therethrough. Thus, it will be seen that movement of the upper member 31 of longitudinal partition 30 toward the lever end of the grid structure 16, as by elevating member 32 relative to member 33 as will hereinafter be more specifically described, will cause the inclined cross walls or partitions 61 to straighten up or move into a substantially vertical position whereby the parallelogram-shaped compartments 17 are changed into a substantially square or rectangular form to thereby enlarge the compartments. The construction and arrangement of the various parts of the unitary grid structure are such that one lever having a single direction of motion will suffice to lift the grid 16 together with ice adhering thereto 70 75

relative to the tray 15, elevate rigid metal members 31 and 32 relative to the rigid metal member 33 of grid 16, and move grid member 31 lengthwise of grid member 32 to rotate or swing the rigid transverse metal walls 61 to enlarge the ice compartments 17.

Assume that water has been frozen in the freezing device in the form of ice blocks 75 in the compartments 17, by the cooling effect produced by a cooling element or evaporator of a refrigerating system, and removal or harvesting of these ice blocks is desired. The tray handle 27 is grasped by the hand and pulled outwardly, thus causing same to pivot about its pivotal mounting 28 and move downwardly. This initial downward movement of handle 27 causes the cam surface or surfaces 29 thereon to bear against the evaporator to break the ice bond between the freezing device and the evaporator. The freezing device can, thereafter, be readily removed from its support in or on the evaporator. After removal of the freezing device from the evaporator of the refrigerating system, handle end 46 of lever 45 on grid 16 is grasped by the hand and elevated 25 to cause the lever to rotate about its pivotal mounting pin or stud 51. Initial upward movement of lever 45 causes the short end 47 thereof to engage the rim 23 at the back end of tray 15 and apply force to the tray to elevate the unitary 30 grid structure 16 and the ice blocks 75 adhering thereto relative to the tray of the freezing device. The enlarged portion 54 of slot 53 in member 32 permits the initial movement of lever 45 to be carried out without moving any of the ice block 35 compartment walls or partitions relative to others thereof. The position of the initial movement of lever 45 of the device is illustrated in Fig. 3 of the drawings and it will be noted that the grid 16 and ice blocks 75 bonded thereto are 40 raised away from the bottom wall 19 of tray 15. The bond between the ice and tray 15 having now been broken permits the unitary grid structure 16 to be removed from the tray for the purpose of releasing ice blocks 75 from walls of the grid. 45 After grid 16 has been removed from tray 15, further elevation or rotation of lever 45 about its pivotal mounting 51 causes the pin or stud 52 carried by the lever to apply force to walls of the angularly disposed slot 53 to thereby lift the lever end of a second member or member 32 of longitudinal partition 30 relative to the first or lower member 33 thereof. Elevation of member 32 about its pivot 42 causes the third member or member 31 of longitudinal partition 30 50 to move lengthwise of the second member 32 in a direction toward the lever end of the grid structure or toward the wall portion 56 of the enlarged end portion 36 of member 32 to close the gap between member 31 and wall portion 56 (see Fig. 4). This lengthwise movement of member 31 relative to member 32, during elevation of these members of the longitudinal partition 30 relative to the first or a lower member 33 thereof, applies force to the transverse walls or 55 partitions 61 to swing or rotate same within the slots 57 and 58. The swinging or rotating movement of partitions 61 moves them out of their normal acute angled disposition into a substantially vertically position which enlarges the compartments 17. Movement of the rigid metal walls or partitions of grid structure 16 relative to one another in the manner described and as illustrated in Fig. 4 of the drawings breaks the bond between the ice blocks 75 and the grid 60 walls or partitions and the enlarging of the ice 75

block compartments 17 causes the blocks 75 to be liberated from the unitary grid structure. In Fig. 4 of the drawings, I have shown the ice blocks 75 in dot-dash lines within the compartments 17 after the walls of grid 16 have been moved merely to illustrate the change in form or enlargement of the normally parallelogram-shaped ice compartments. It is to be understood, however, that, when the walls of the grid have been moved to the position shown in Fig. 4 10 as described, the ice blocks 75 will be instantly liberated from the grid and will freely fall into the tray 15 or other suitable receptacle as shown in full lines in the drawing.

From the foregoing it will be seen that, by 15 dividing the longitudinal grid partition into three parts and causing movement of one part thereof in one direction relative to another part thereof simultaneously with moving still another part thereof in another direction while moving the 20 transverse grid walls, I have separated the forces acting to dislodge ice blocks from the unitary grid structure to facilitate their removal with a minimum of effort manually exerted upon the operating lever. The forces applied to the ice 25 blocks in different directions relative to one another prevent undue shattering of the ice blocks. My improved grid structure is of low cost, strong and durable, and yet operable by one lever adapted to move in a single direction of motion 30 for separating the grid together with ice blocks bonded thereto from the tray and for moving the grid walls relative to one another for liberating ice blocks therefrom. My improved grid structure is constructed entirely of metal to thereby 35 retain the fast freezing characteristics of metal tray and grid combinations.

While the form of embodiment of the invention as herein disclosed, constitutes a preferred form, it is to be understood that other forms 40 might be adopted, all coming within the scope of the claims which follow.

What is claimed is as follows:

1. A unitary grid structure for disposition in an ice tray and removable therefrom as a unit, 45 said grid structure comprising a longitudinal partition and a plurality of partitions disposed in spaced apart relation along the length of said longitudinal partition and extending outwardly therefrom, said longitudinal partition including 50 three superimposed members disposed in substantially the same vertical plane with one another and cooperating with said outwardly extending partitions to form walls of a plurality of ice block compartments, means for connecting 55 said three members of said longitudinal partition and said plurality of outwardly extending partitions together in movable relation to one another, means carried by said grid structure for applying force between a first one and a second one of 60 said members of said longitudinal partition to elevate a portion of said second one and the third one of said members together with said outwardly extending partitions relative to said first one of said members, and the connection of said 65 members being so constructed and arranged that the elevation of said second and said third members with said outwardly extending partitions relative to said first member causes movement of said third member lengthwise of said second 70 member to thereby rotate said outwardly extending partitions for liberating ice blocks from said compartments.

2. A unitary grid structure for disposition in an ice tray and removable therefrom as a unit, 75

- said grid structure comprising a longitudinal partition and a plurality of partitions disposed in spaced apart relation along the length of said longitudinal partition and extending outwardly therefrom, said longitudinal partition including three superimposed members disposed in substantially the same vertical plane with one another and cooperating with said outwardly extending partitions to form walls of a plurality of ice block compartments, means for connecting said outwardly extending partitions to at least two of said three members of said longitudinal partition, means for connecting said three members of said longitudinal partition together in movable relation to one another, means carried by said grid structure for applying force between a first one and a second one of said members of said longitudinal partition to elevate a portion of said second one and the third one of said members together with said outwardly extending partitions relative to said first one of said members, and the connection of said members being so constructed and arranged that the elevation of said second and said third members with said outwardly extending partitions relative to said first member simultaneously moves said third member lengthwise of said second member and rotates said outwardly extending partitions to liberate ice blocks from said compartments.
3. In combination, a tray having a grid disposed therein, said grid comprising a longitudinal partition and a plurality of partitions disposed in spaced apart relation along the length of said longitudinal partition and extending continuously through the plane thereof outwardly from its sides, said longitudinal partition including three superimposed members disposed in substantially the same vertical plane with one another and cooperating with said outwardly extending partitions to divide the interior of said tray into rows of ice block compartments, means for connecting said three members of said longitudinal partition and said plurality of outwardly extending partitions together in movable relation to one another to form a unitary removable grid structure, means carried by said grid structure for applying force to said tray for elevating the grid together with ice blocks adhering thereto relative to the tray, said means being arranged to impart a force between a first one and a second one of said members of said longitudinal partition to elevate a portion of said second one and the third one of said members together with said outwardly extending partitions relative to said first one of said members after the unitary grid structure and ice blocks have been elevated relative to the tray, and the connection of said members being so constructed and arranged that the elevation of said second and said third members with said outwardly extending partitions relative to said first member causes movement of said third member lengthwise of said second member to thereby rotate said outwardly extending partitions for liberating ice blocks from said grid structure.
4. A unitary grid structure for disposition in an ice tray and removable therefrom as a unit, said grid structure comprising a longitudinal partition and a plurality of partitions disposed in spaced apart relation along the length of said longitudinal partition and extending outwardly therefrom, said longitudinal partition including three superimposed members disposed in substantially the same vertical plane with one another and cooperating with said outwardly extending partitions to form walls of a plurality of ice block compartments, said outwardly extending partitions being normally disposed at an acute angle with respect to the disposition of said longitudinal partition to provide said ice block compartments with a parallelogram form in one direction of cross section therethrough, means for connecting said three members of said longitudinal partition and said plurality of outwardly extending partitions together in movable relation to one another, means carried by said grid structure for applying force between a first one and a second one of said members of said longitudinal partition to elevate a portion of said second one and the third one of said members together with said outwardly extending partitions relative to said first member simultaneously moves said third member lengthwise of said second member and rotates said outwardly extending partitions out of their normal acute angled disposition to enlarge said compartments for liberating ice blocks from said grid structure.
5. A unitary grid structure for disposition in an ice tray and removable therefrom as a unit, said grid structure comprising a longitudinal partition and a plurality of partitions disposed in spaced apart relation along the length of said longitudinal partition and extending outwardly therefrom, said longitudinal partition including three superimposed members disposed in substantially the same vertical plane with one another and cooperating with said outwardly extending partitions to divide the interior of said tray into rows of ice block compartments, said outwardly extending partitions being normally disposed at an acute angle with respect to the disposition of said longitudinal partition to provide said ice block compartments with a parallelogram form in one direction of cross section therethrough, means for connecting said three members of said longitudinal partition and said plurality of outwardly extending partitions together in movable relation to one another, means carried by said grid structure for applying force between a first one and a second one of said members of said longitudinal partition to elevate a portion of said second one and the third one of said members together with said outwardly extending partitions relative to said first member simultaneously moves said third member lengthwise of said second member and rotates said outwardly extending partitions out of their normal acute angled disposition to enlarge said compartments for liberating ice blocks from said grid structure.
6. In combination, a tray having a grid disposed therein, said grid comprising a longitudinal partition and a plurality of partitions disposed in spaced apart relation along the length of said longitudinal partition and extending continuously through the plane thereof outwardly from its sides, said longitudinal partition including three superimposed members disposed in substantially the same vertical plane with one another and cooperating with said outwardly extending partitions to form walls of a plurality of ice block compartments, said outwardly extending partitions being normally disposed at an acute angle with respect to the disposition of said longitudinal partition to provide said ice block compartments with a parallelogram form in one direction of cross section therethrough, means for connecting said three members of said longitudinal partition and said plurality of outwardly extending partitions together in movable relation to one another, means carried by said grid structure for applying force between a first one and a second one of said members of said longitudinal partition to elevate a portion of said second one and the third one of said members together with said outwardly extending partitions relative to said first member simultaneously moves said third member lengthwise of said second member and rotates said outwardly extending partitions out of their normal acute angled disposition to enlarge said compartments for liberating ice blocks from said grid structure.

tending partitions to divide the interior of said tray into rows of ice block compartments, said outwardly extending partitions being normally disposed at an acute angle with respect to the disposition of said longitudinal partition to provide said ice block compartments with a parallelogram form in one direction of cross section therethrough, means for connecting said three members of said longitudinal partition and said plurality of outwardly extending partitions together in movable relation to one another to form a unitary removable grid structure, means carried by said grid structure for applying force to said tray for elevating same together with ice blocks adhering thereto relative to the tray, said means being arranged to also impart a force between a first one and a second one of said members of said longitudinal partition to elevate a portion of said second one and the third one of said members together with said outwardly extending partitions relative to said first one of said members after the unitary grid structure and ice blocks have been elevated relative to the tray, and the connection of said members being so constructed and arranged that the elevation of said second and said third members with said outwardly extending partitions relative to said first member causes movement of said third member lengthwise of said second member to thereby rotate said outwardly extending partitions out of their normal acute angled disposition to enlarge said compartments for liberating ice blocks from said grid structure.

7. A unitary grid structure for disposition in an ice tray and removable therefrom as a unit, said grid structure comprising a longitudinal partition and a plurality of partitions disposed in spaced apart relation along the length of said longitudinal partition and extending outwardly therefrom, said longitudinal partition including three superimposed members disposed in substantially the same vertical plane with one another and cooperating with said outwardly extending partitions to form walls of a plurality of ice block compartments, means for connecting said three members of said longitudinal partition and said plurality of outwardly extending partitions together in movable relation to one another, a lever pivotally carried by a first one of the three members of said longitudinal partition and having a connection with a second one of said members, said lever being operable to apply force between said first member and said second member to elevate a portion of said second member and the third one of said members together with said outwardly extending partitions relative to said first member, and the connection of said members being so constructed and arranged that the elevation of said second and said third members with said outwardly extending partitions relative to said first member causes movement of said third member lengthwise of said second member to thereby move said outwardly extending partitions relative to said members for liberating ice blocks from said compartments.

8. A unitary grid structure for disposition in an ice tray and removable therefrom as a unit,

said grid structure comprising a longitudinal partition and a plurality of partitions disposed in spaced apart relation along the length of said longitudinal partition and extending outwardly therefrom, said longitudinal partition including three members cooperating with said outwardly extending partitions to form walls of a plurality of ice block compartments, means for connecting said three members of said longitudinal partition and said plurality of outwardly extending partitions together in movable relation to one another, means for applying force between a first one and a second one of said members of said longitudinal partition to elevate a portion of said second one and the third one of said members together with said outwardly extending partitions relative to said first one of said members, and the connection of said members being so constructed and arranged that the elevation of said second and said third members with said outwardly extending partitions relative to said first member causes movement of said third member lengthwise of said second member to thereby move said outwardly extending partitions for breaking the bond between ice blocks and the compartment walls and for liberating ice blocks from said compartments.

9. A unitary grid structure for disposition in an ice tray and removable therefrom as a unit, said grid structure comprising a longitudinal partition and a plurality of partitions disposed in spaced apart relation along the length of said longitudinal partition and extending outwardly therefrom, said longitudinal partition including three superimposed members disposed in substantially the same vertical plane with one another and cooperating with said outwardly extending partitions to form walls of a plurality of ice block compartments, said outwardly extending partitions being normally disposed at an acute angle with respect to the disposition of said longitudinal partition to provide said ice block compartments with a parallelogram form in one direction of cross section therethrough, means for connecting said outwardly extending partitions to at least two of said three members of said longitudinal partition, means for connecting said three members of said longitudinal partition together in movable relation to one another, means for applying force between a first one and a second one of said members of said longitudinal partition to elevate a portion of said second one and the third one of said members together with said outwardly extending partitions relative to said first one of said members, and the connection of said members being so constructed and arranged that the elevation of said second and said third members with said outwardly extending partitions relative to said first member moves said third member relative to said second member and also moves said outwardly extending partitions out of their normal acute angled disposition to enlarge said compartments for breaking the bond between ice blocks and the compartment walls and for liberating ice blocks from said grid structure.

JAMES W. JACOBS.
